UNITED STATES PATENT OFFICE

HENRY STINSON JOHNS, OF HAMILTON, ONTARIO, CANADA, ASSIGNOR TO BANCROFT HOLDINGS LIMITED, OF HAMILTON, ONTARIO, CANADA, A CORPORATION OF ONTARIO

PLASTER MIXING MACHINE

Application filed May 28, 1930. Serial No. 456,653.

My invention relates to improvements in machines for mixing plaster and the like, and the object of my invention is to construct a machine which is particularly adapted for mixing materials for tinted plasters and also dry plaster mixtures composed of various granular substances.

The object of my invention is to utilize a standard horizontal revolving drum and to furnish such drum interiorly with spiral means for carrying the mixture towards the central portion of the drum, and also to furnish the drum with other rotary mixing members tending to carry the mixture in opposite directions to its movement under the influence of the spiral means.

A further object of my invention is to furnish a mixture filling and removal trap door in the drum and to surround the trap door containing portion of the drum with a shield in order to facilitate the ready removal of the mixture from the drum, as shall be hereinafter explained.

My invention relates to improvements in mixing machines all as hereinafter more particularly described and illustrated in the accompanying drawings in which:

Fig. 1 is a plan view of my device, part of the drum being broken away.

Fig. 2 is a vertical cross sectional view taken through the line 2—2 Fig. 1.

Fig. 3 is a perspective view of a fragmentary portion of the drum and trap door.

Fig. 4 is an enlarged side elevational view partly in section of a pair of mixing members.

Fig. 5 is a perspective view of one of my spade mixers, and

Fig. 6 is a perspective view of one of my trowel mixers.

Like characters of reference indicate corresponding parts in the different views in the drawings.

My mixer comprises a horizontal rotary drum 1 freely carried upon a central horizontal rotary shaft 2 mounted in a pair of end bearings 3 which are carried upon supporting brackets 4 so that the drum is supported some little distance above the floor 55 upon which the machine is supported.

Extending in parallel relation to the drum 1, I furnish a driving shaft 5 which is supported in a pair of end bearings 6 also carried upon the brackets 4. 7 is a gear carried upon one end of the shaft 2 and meshing with a pinion 8 secured to the corresponding end of the driving shaft 5.

In the vicinity of the other end of the shaft 5 I furnish a sleeve 9 thereon, such sleeve extending through the bearing 6 and carrying upon its outer end a pair of belt pulleys 10 and 11, the pulley 10 being an idler pulley and the pulley 11 secured to the sleeve. 12 is a gear secured to the adjacent end of the drum 1 and meshing with a pinion 13 secured upon the inner end of the sleeve 9. Upon the end of the shaft 5 protruding from the sleeve 9 I position a pair of belt pulleys 14 and 15, 14 being an idler pulley and the pulley 15 being secured to the shaft. 70

Interiorly of the drum 1 and carried upon the shaft 2 I furnish a plurality of radially extending rods 16 which extend from a plurality of blocks 17 clamped and keyed to the shaft. The outer ends 18 of the alternate rods 16 carry a pair of spiral ribbons 19 and 20 which convolute in opposite directions, each spiral ribbon occupying one half of the drum. The ribbons extend through slots 21 in the ends of the rods 16. The rods 16 also carry my spade and trowel members 22 and 23, such members being of the form illustrated in Figures 5 and 6. Each spade 22 is formed with a central sleeve 24 to receive a rod, a set screw 25 being provided whereby the spade can be secured at any desired angle upon its rod. The trowel members 23 are each formed with lugs 26 by means of which they are secured to blocks 27 upon the ends of the rods 16 through the medium of pins 28 which extend through the lugs and blocks. Each of the blocks 27 is formed with a pair of lugs 29 having threaded orifices therein through which adjusting screws 30 extend and bear against the faces of the trowels whereby the angularity of such trowels may be adjusted. 85

In the central portion of the drum 1, I provide a rectangular trap door 31 which is carried upon a rectangular flanged frame 100

32 surrounding the mixture filling and emptying orifice 33 in the drum. This trap door can be removably secured in position in the frame in any desirable manner, as illustrated in the drawings I furnish a pair of studs 34 projecting from one edge of the trap door adapted to be contained within a pair of orifices 35 in the corresponding edge of the door frame 32, and extending through the opposite edge of the trap door I furnish a U shaped bolt 36 which removably extends into the orifices 37 in the corresponding edge of the door frame. The bolt 36 is held in engagement with the orifices 37 by a spring 38 extending between the end of the bolt and the edge of the trap door, the bolt being withdrawn against the resiliency of the spring 38 out of the orifices 37 when it is desired to remove the trap door. Surrounding the central portion of the drum 1 in which the trap door is contained I mount a substantially circular shield 39 which is formed with an opening 40 in its top, and a chute opening 41 in its bottom which extends through the floor 55; a hopper or other suitable receptacle being positioned underneath the floor 55.

When my mixer is being filled with the various dry plaster ingredients, the drum 1 is in the position illustrated in Figures 1 and 2, the trap door 31 being uppermost underneath the opening 40 in the shield. The trap door is opened and the mixture deposited in the drum, after which the trap door is locked in place and the mixer is ready for operation.

The four pulleys 10, 11, 14 and 15 carry a pair of shifting driving belts (not shown) and when the mixer is stopped the pair of belts run upon the idler pulleys 14 and 10, and when it is desired to run the mixer the belts are shifted over onto the driving pulleys 15 and 11; the belts run in opposite directions so that the driving pulleys also run in opposite directions. If the driving pulley 15 is rotating in a clockwise direction the shaft 5 to which it is secured and pinion 8 will also rotate in a clockwise direction with the consequent anti-clockwise rotation of the gear 7, shaft 2, spiral ribbons 19 and 20, and the mixing spades and trowels. As the driving pulley 11 is rotated in an anti-clockwise direction, the sleeve 9 and pinion 13 will also rotate in an anti-clockwise direction with the consequent clockwise rotation of the gear 12 and the drum 1. It will be therefore understood that the drum rotates in an opposite direction to the mixing members contained therein.

The convolutions of the spiral ribbons 19 and 20 are such that their rotative action carries the material contained within the drum towards its centre and the inclination of the spade members 22 such that spade members have a tendency to throw the material back towards the ends of the drum. The trowel members 23 which can be adjusted so

that they lie rather close to the inner surface of the drum prevent the material from packing, in that they bear down on the agitated material lying in the bottom of the drum to break up any lumps contained therein and work the materials in together.

When the mixer has been run for some five or ten minutes which is the average time for thoroughly mixing all the ingredients of any dry plaster mixture or the like, the belt upon the driving pulley 11 is shifted across to the idler pulley 10, so that the drum 1 is free and not positively rotated. Upon the other end of the drum to the gear 12 I furnish a pawl member 42 which projects therefrom and engages the bracket 4 during each rotation of the drum 1. This pawl however is so mounted that it permits the drum to rotate in its mixing direction of rotation, but engages the bracket 4 and prevents it from rotating in the opposite direction. When the driving belt is moved from the pulley 11 to the pulley 10 as previously explained, the drum 1 being free will be reversed in movement and carried around through the friction of the mixing members until the pawl 42 engages the bracket, when the drum will stop. The pawl is so positioned in regard to the trap door that when this engagement occurs the trap door will be underneath the opening 40 in the shield 39. The trap door is then removed and the driving belt moved back from the idler pulley 10 onto the driving pulley 11 when the drum 1 will recommence its normal rotative movement.

As the material is carried to the centre of the drum by the spiral ribbons 19 and 20 and the trap door is open, it will be obvious that each time the drum rotates and the trap door reaches the bottom of rotation that the material will spill out of the drum through the chute 41 into the hopper or other receptacle below the floor 55. When the drum has been rotated for a couple of minutes all the material will have been removed therefrom after which the driven rotation of the drum is first stopped so that the drum is carried around to the position wherein its trap door lies under the opening in the shield, the rotation of the mixing members then being brought to a standstill.

From the foregoing description it will be apparent that I have devised a particularly simple and effective type of mixer wherein the ingredients are thoroughly and completely mixed in a very short period of time through the provision of the opposed agitating means herebefore described and also that I have provided an operating means whereby the mixing drum can be very readily filled and emptied.

What I claim as my invention is:

1. In a material mixing machine, a horizontally rotatable drum, driving means for

rotating the drum in one direction, a central shaft within the drum independently rotated in the opposite direction, a trap door positioned substantially centrally of the drum, a 5 pair of spiral members extending interiorly of the drum and convolving in opposite directions to the vicinity of the trap door, and a plurality of spade members also carried by the shaft and extending through the spiral 10 members, said spade members being oppositely inclined to the convolutions of the spiral members through which they extend, and a shield surrounding the portion of the 15 drum containing the trap door and formed with a material inlet orifice in its top and a material discharge orifice in its bottom.

2. In a material mixing machine, a horizontally rotatable drum, driving means for rotating the drum in one direction, a central shaft within the drum independently rotated in the opposite direction, a trap door positioned substantially centrally of the drum, a pair of spiral members extending interiorly of the drum and convolving in opposite 20 directions to the vicinity of the trap door, and means permitting the drum rotation in one direction but restraining it against rotation in the opposite direction in a position with the trap door uppermost, a 25 shield surrounding the centre of the drum and formed with an orifice in its top, and a chute formed in the bottom of the shield across the upper end of which the trap door passes.

35 HENRY STINSON JOHNS.
